BOWLING GLOVE

Donald J. Carter, Miami, Fla., and Frank Esposito, Paramus, N.J., assignors to National Athletic Supply Corporation, Paramus, N.J.

Filed Sept. 14, 1973, Ser. No. 397,602

Term of patent 14 years

Int. Cl. D2—06

U.S. Cl. D2—361

Fig. 1

Fig. 2

Fig. 3

Fig. 4

Fig. 5

Fig. 6

FIG. 1 is a bottom plan view of a bowling glove showing our new design;

FIG. 2 is a top plan view thereof;

FIG. 3 is a side elevational view thereof as seen from the right-hand side of FIG. 2;

FIG. 4 is a front elevational view thereof as seen from the top of FIG. 2;

FIG. 5 is a side elevational view thereof as seen from the left of FIG. 2; and

FIG. 6 is a rear elevational view thereof as seen from the bottom of FIG. 2.

We claim:

The ornamental design for a bowling glove, as substantially shown and described.
